UNITED STATES PATENT OFFICE

2,504,441

GOVERNOR FOR PORTABLE TOOLS

Walter G. Mitchell, Aurora, Ill., assignor to Independent Pneumatic Tool Company, Chicago, Ill., a corporation of Delaware

Application February 16, 1946, Serial No. 648,065

5 Claims. (Cl. 121—34)

1

This invention relates to improvements in governors especially adapted for portable pneumatically operated tools.

The principal object and purpose of my invention is to locate the governor device within the tool motor to simplify its construction and to reduce the overall dimensions of the tool for compactness and convenience in handling.

A further object of my invention is to utilize certain of the longitudinal passages in the rotor of the motor to mount the centrifugally responsive weight elements of the governor device.

A further object of my invention is to provide the rotor with a diametric or transverse cross-slot to accommodate a cross-bar or other operative part of the governor device for actuating the valve means controlled by the governor.

A further object of my invention is to provide in the specific embodiment herein shown a cam connection between the weight elements and the cross-bar to insure movement of the latter in opposite directions in response to the valve spring and centrifugal force, respectively.

The invention consists further in the structural features and combination of parts herein-after described and claimed.

In the accompanying drawings—

Fig. 1 is a side elevational view, partly in longitudinal section, of a portable pneumatically operated impact tool having a governor device located within the tool motor in accordance with my invention;

Fig. 2 is a diametric sectional view taken on line 2—2 of Fig. 1;

Fig. 3 is a longitudinal sectional view on a larger scale and detailing the governor device, said section being taken on line 3—3 of Fig. 2;

Fig. 4 is an elevational view of one of the weight elements of the governor removed from the tool;

Fig. 5 is a top plan view of the cross-bar of the governor device, also removed from the tool for the purposes of illustration;

Fig. 6 is a side view of a weight element provided with an increased mass on one side;

Fig. 7 is a top plan view of said modified weight element;

Fig. 8 is a fragmentary vertical sectional view with parts in elevation of a modified form of governor construction to be hereinafter described; and

Fig. 9 is a horizontal sectional view taken on line 9—9 of Fig. 8 to show a detail of construction.

The tool shown in Fig. 1 has a rotary motor 1 and an outer casing 2 comprising an upper section 3 housing the motor and a lower section 4

2

housing the impact clutch of the tool, said clutch having a spindle 5 extending from the lower end of the tool to mount and drive a nut or bolt engaging socket 6 as in tool devices of this character.

The tool has a side handle 7 through which extends a passage (not shown) containing a spring biased throttle valve 8 to control the main supply of pressure fluid or compressed air to the tool motor 1 for operating it. The air supply hose (not shown) is connected to the handle 7 at its outer end, there being a hose connecting fixture 9 at such end of the handle as is shown. The valve 8 is the starting and stopping valve of the tool and is opened by depressing a trigger block 10 slidably mounted in the handle 7.

The tool motor 1, being of the rotary type, has a rotor 11 having blades 12 operating in radial slots 13 in the rotor and a cylinder 14 closed at its opposite ends by end plates 15, 15. The motor case or section 3 in conjunction with cylinder 14 are provided with a porting system for operating the rotor 11 in reverse directions as in tools of the character displayed. The impact clutch is of the character which delivers rotational hammer blows to the spindle 5 for nut and bolt tightening and loosening purposes, respectively. The lower trunnion 16 of the rotor 11 extends through the lower end plate 15 and is splined or directly connected with the clutch shaft 17.

Formed in the motor case 3 at one side of the tool motor is a supply passage 18 connecting with a cross-passage 19 in the top part of the tool case above the motor 1. The passage 19 is divided by a fixed sleeve or housing section 20 having diametric ports 21, 22, the port 21 connecting with the passage section 19a and the port 22 connecting with the passage section 19b. The latter section 19b leads to an inlet port 23 of the porting system of the tool. The reversing mechanism for this porting system need not be shown, forming no part of the present invention.

The governor device for the tool in accordance with my invention is located within the rotor 11 for compactness and to reduce the overall length to the tool. This governor device in its preferred form is constructed as follows:

The rotor 11 of the tool motor to lessen its weight is provided with the usual axially extending, circumferentially spaced, cylindrical chambers or passages 24, 24. Two diametrically opposite of these passages or bores 24a, 24a are employed to mount and house the centrifugal weights 25, 25 of the governor device. There is one weight 25 in each passage 24a and, as shown

in Fig. 3, each weight 25 rests at its lower end on a plug 26 tightly fitted within the passage 24a and closing its lower end. Here, the lower end of the weight element 25 is rounded and seats in a concave socket or recess 27 so that the weight element will readily rock or tilt in response to centrifugal force and spring pressure, respectively. Each recess 27 is offset outwardly from the longitudinal center line of its passage 24a, whereby the weight elements 25 will stand at inwardly tilted angles on opposite sides of the rotor axis when the governor device is at rest.

The weight elements 25 extend along their respective passages 24a and have their upper inner ends beveled at 28 to increase the angle at which the weights stand when at rest. At this time, the weights 25 bear against sleeves 29 fitted in the passages 24a to close openings or slots 30 at their outer sides as shown in Fig. 3. The sleeves 29 fit between the plugs closing the opposite ends of the passages 24a, the upper plug being marked 31. The sleeves 29 are removed to open the slots 30 to insert the cross-bar 32 or equivalent means into or remove it from the rotor 11.

Provided in the rotor 11 in the region of the upper beveled ends of the weight elements 25 is a transverse or cross-slot 33 opening into the passages 24a and aligned with the slots 30 as shown in Figs. 2 and 3. Located in the cross-slot 33 is the laterally narrow cross-bar 32 having its end positions 34, 34 fitting in bifurcations 35 at the upper ends of weight elements. The cross-bar has downwardly and outwardly inclined surfaces 36 at its ends to co-act with complementary shaped cam surfaces 37 at the bottoms of the bifurcations 35.

Located in the housing 20 in axial alignment with the rotor 11 is an inlet valve 38 subject to the control of the governor device. Said valve 38 is slidably mounted in the housing 20 and has a depending stem 39 extending downwardly into a bore in the upper trunnion 40 of the rotor 11. Said valve 38 is biased to open position by a coiled spring 41 contained within the housing 20 and retained therein by a screw-cap 42 closing its upper end.

Also mounted in the bore in the upper trunnion 40 of the rotor 11 is a rod 43 fitting between and engaging the cross-bar 32 and the valve stem 39, respectively. The spring 41 holds the parts in contact and under the desired tension as shown in Fig. 3, the upper end of the rod being against the valve stem 39 and the lower end of the rod being against the cross-bar 32 within the cross-slot 33. The arrangement described and shown holds the end portions 34 of the cross-bar 32 in the bifurcations 35 and the inclined surfaces 36, 37 in contact or operative engagement.

The governor device shown and described operates as follows:

When at rest or not overcoming the tension of the valve spring 41, the weight elements 25 stand in their inwardly inclined positions as shown in Fig. 3. The ports 21, 22 are at this time fully open and the valve 38 furnishes a full volume of compressed air to the tool motor 1 from the throttle valve 8. Under speed of the motor 1 centrifugal force tilts the weight element 25 outwardly and the cross-bar 32 is moved axially to close or partially close the valve 38. This reduces the air volume furnished to the tool motor and the latter rotates or idles at the desired speed, a limited supply of live air being supplied to the motor through the valve 38.

When the tool is applied to the work, its speed

of rotation is reduced by the impressed load and the weight elements 25 are moved into their inwardly tilted positions by the downward pressure or action of the spring 41 as it opens the valve 38.

The outward tilting movement of the weight elements 25 is by centrifugal force and the cross-bar 32 serves to move the valve 38 towards closed position. The movement of the cross-bar 32 in the opposite direction by the valve spring 41 returns the weight elements 25 to their inwardly tilted positions when centrifugal force is reduced. This movement is due to the coaction of the inclined or cam surfaces 36, 37 at the ends of the cross-bar 32 and on the weight elements 25, respectively. An outward movement of the weight elements 25 raises the cross-bar 32, while a downward movement of the cross-bar 32 moves the weight elements to their inwardly tilted positions.

To increase the mass of a weight element 25 to make it more responsive to an inward tilting movement and centrifugal force, I may increase the section of the weight element on its inner side as indicated by the dotted line *a* in Fig. 3 and full lines in Figs. 6 and 7. In the last two figures the modified weight element is marked 25a.

The cross-slot 33 intersects or opens into the passages 24a as heretofore mentioned. The sleeves 29 are slotted at 44 to register with the cross-slot 33 to offer no interference to the passage of the cross-bar 32 into and out of the passages 24a. The governor is assembled by inserting the cross-bar 32 into the cross-slot 33 through one of the side openings 39 in the rotor 11 and then the weight elements 25 are placed in the chambers 24a astride the ends 34 of the cross-bar, the bifurcations 35 of the weight elements serving this purpose. The sleeves 29 are then inserted into the chambers 24a to close the outside openings 30 and the plugs 26 and 31 are fitted into the opposite ends of the chambers to hold the sleeves 29 in place. The cross-bar 32 being laterally narrow makes the slot structure 30, 33, 35 and 44 similarly narrow and the governor parts may be made to fit within the confines of a tool rotor 11 of a relatively small size.

The modified construction of my invention as shown in Figs. 8 and 9 employs centrifugally responsive spherical or ball elements 25b, 25b within the rotor 11 instead of the pivoted weight elements 25. The ball elements 25b are mounted within the tubes 29a, 29a on transverse lands or track-ways 45 therein in the region of the cross-slot 32a in the rotor as shown. The cross-bar 33a extends through said cross-slot 32a as in the previous figures, and has its end portions 46 in the axially extending chambers 24a with inclined surfaces 47 co-acting with the ball elements 25b as detailed in Fig. 8. The tubes 29a close the side openings 60 30 in the rotor as before. As shown in Fig. 8, the ball elements 25b are stopped by tapered portions 48 made by drilling in the rotor at the inner ends of the track-ways. The valve stem or actuating rod 49 engages the cross-bar 32a and is lifted by the ball elements on their outward movement in response to centrifugal force on the rotation of the rotor. This lifting action of the rod 49 at an increase in speed closes the valve 38 as before, the ball elements 25b having the diameter 70 for the purpose.

With the governor device located and housed within the tool motor in accordance with my invention, the tool is considerably reduced in overall length as compared to the exteriorly arranged governors heretofore employed. The tool is also

more compact for ease in handling and manipulation. With the governor weights or their equivalents located within the passages or bores 24a usually provided in the motor rotor, the governor device is adequately housed and the design is simple and inexpensive in construction.

The details of construction and arrangement of parts shown and described may be variously changed and modified without departing from the spirit and scope of my invention, except as pointed out in the annexed claims.

I claim as my invention:

1. In combination, a pressure fluid actuated rotary motor having a rotor, a valve for controlling the supply of pressure fluid to said rotor, means for opening said valve, and governor means responsive to centrifugal force in the rotation of the rotor to close said valve, said governor means being carried by and housed within the rotor and having a cross-bar comprising a thin flat plate extending cross-wise of the rotor in a narrow diametric slot therein in a plane coincident with the axis of said rotor and the walls of said slot closely conforming to the sides of said plate for slidably engagement therewith, and elongated centrifugally responsive elements located at and operable on the opposite end portions of the cross-bar in closing said valve, said elements acting on inclined cam surfaces at the ends of said bar, said elements and the valve being located on opposite sides of the bar in the axial direction of the rotor, said elements extending longitudinally of the rotor and co-acting at its opposite ends on the rotor and the bar, respectively.

2. In combination, a pressure fluid actuated rotary motor having a rotor, a valve for controlling the supply of pressure fluid to said rotor, means for opening said valve, and governor means responsive to centrifugal force in the rotation of the rotor to close said valve, said governor means being carried by and housed within the rotor and having elongated weighted elements located in and extending lengthwise of axially extending chambers in the rotor on opposite sides of and substantially parallel to its rotary axis, said elements being tiltably mounted on one of their respective ends in said chambers and being formed with bifurcations at the other of their respective ends, and a cross-bar in a diametric slot in the rotor between and opening into said chambers, said cross-bar having its opposite ends in said chambers and extending through said bifurcations in the adjacent portions of said elements and said bifurcations being of greater length and extending beyond the portions of the cross bar extending therethrough for increasing the effect of centrifugal force thereon, and complementary inclined surfaces on the cross-bar and at the bottoms of the bifurcations, respectively.

3. In combination, a pressure fluid actuated rotary motor having a rotor, a valve for controlling the supply of pressure fluid to said rotor, means for operating said valve, and governor means responsive to centrifugal force in the rotation of the rotor to close said valve, said governor means being carried by and housed within the rotor and having elongated weighted elements located in and extending lengthwise of axially extending

chambers in the rotor on opposite sides of and substantially parallel to its rotary axis, and a cross-bar in a diametric slot in the rotor between and opening into said chambers, said cross-bar having its ends in said chambers and operated on by one of the corresponding end portions of the weighted elements in the closing of said valve, and plug members closing the lower ends of the chambers and having curved recesses providing tiltable mountings for the other corresponding ends of the weighted elements in said chambers.

4. In combination, a pressure fluid actuated rotary motor having a rotor having longitudinally extending chambers on opposite sides of and substantially parallel to the rotary axis of said rotor, a cross-slot in said rotor between and intersecting said chambers, a valve for controlling the supply of pressure fluid to said rotor, means for opening said valve, governor means responsive to centrifugal force in the rotation of the rotor to close said valve and having centrifugally responsive elements and a cross-bar in said chambers and the cross-slot, respectively, said chambers having side openings in the outer side of the rotor to pass said bar in its insertion into and withdrawal from the cross-slot in the rotor, and means carried by the rotor for normally closing said side openings.

5. In combination, a pressure fluid actuated rotary motor having a rotor having longitudinally extending chambers on opposite sides of and substantially parallel to the rotary axis of the rotor, a cross-slot in said rotor between and intersecting said chambers, a valve for controlling the supply of fluid pressure to said rotor, means for opening said valve, governor means responsive to centrifugal force in the rotation of the rotor to close said valve, said governor means having centrifugally responsive elements and a cross-bar in said chambers and the cross-slot, respectively, said chambers having side openings in the outer side of the rotor to pass said bar on inserting it into and withdrawing it from said slot, said side openings being in alignment with said slot, and tubular members in said chambers to open and close said side openings.
